(57) **CLAIM**

The ornamental design for a tire sidewall, as shown and described.

DESCRIPTION

FIG. 1 is a perspective view of a tire sidewall showing my new design;

FIG. 2 is a front view thereof;

FIG. 3 is a rear view thereof;

FIG. 4 is a right side view thereof, the left side view being identical;

FIG. 5 is a top view thereof, the bottom view being identical;

FIG. 6 is a fragmentary enlarged front view of the part defined by lines 6-6 of FIG. 2;

FIG. 7 is a fragmentary enlarged front view of the part defined by lines 7-7 of FIG. 2;

FIG. 8 is a fragmentary enlarged front view of the part defined by lines 8-8 of FIG. 2;

FIG. 9 is a fragmentary enlarged cross-section view taken along line 9-9 of FIG. 6;

FIG. 10 is a fragmentary enlarged cross-section view taken along line 10-10 of FIG. 6;

FIG. 11 is a fragmentary enlarged cross-section view taken along line 11-11 of FIG. 7;

FIG. 12 is a fragmentary enlarged cross-section view taken along line 12-12 of FIG. 8; and,

FIG. 13 is a fragmentary enlarged cross-section view taken along line 13-13 of FIG. 8.

Broken lines show environmental portions of a tire sidewall that are not being claimed, and form no part of the claimed design.

1 Claim, 13 Drawing Sheets
